FRAME CONSTRUCTION FOR SOFT-SIDED
LUGGAGE

George G. Barton, Racine, Wis., assignor to Hartmann Company, Racine, Wis., a corporation of Wisconsin

Application April 16, 1947, Serial No. 741,825

1 Claim. (Cl. 190—49)

1

This invention relates to improvements in luggage case frame construction, and more particularly to the frame construction of sections of hand luggage cases of the "soft-sided" or flexible walled type.

Certain types of hand luggage cases, characterized by "soft-sided" or flexible walls, are in extensive service. In a hand luggage case of the type under consideration each case section is formed so that certain major wall portions thereof include only an exterior flexible covering material such as leather, canvas, or the like, and an inner lining fabric. To support the covering material for each case section and to provide interfitting valance portions for the respective sections of a case, each case section must comprise a skeleton-like frame, and in a "soft-sided" type of case it is essential that the case section frames include a minimum number of parts and be devoid of bulk and weight. The frame must reinforce and give rigidity to certain of the walls of the case section, but a frame which materially adds to the weight of the luggage case section is highly objectionable, and additionally, the frame must be such that the outer side wall portions of the case are devoid of reinforcement and stiffening material as the latter will negative the "soft-sided" or flexible nature of the case, it being appreciated that a "soft-sided" case has certain appeals and advantages.

With the foregoing in mind it is, therefore, a primary object of the present invention to provide a luggage case frame construction particularly adapted for "soft-sided" or flexible wall luggage cases, which does not negative or detract from the "soft-sided" nature of the luggage case sections, nor add to the weight of the luggage, but which nevertheless effectively reinforces the luggage case sections in a manner so as to prevent undesirable distortion and flexing of the same when in service.

A further object of the invention is to provide a luggage case frame construction particularly adapted for "soft-sided" luggage cases wherein each case section frame is of outline form with the component parts thereof being mutually interlocked to enhance the rigidity, strength and stability of the case section while permitting limited yieldability thereof.

A further object of the invention is to provide a luggage case frame construction formed of interconnected light weight veneer and fiber elements having recessed and rounded corner portions to permit a smooth and flush application of covering material.

2

A further object of the invention is to provide a luggage case frame construction which results in a light, shape-retaining and durable case of unique and attractive appearance, which is strong and not subject to distortion or damage in ordinary usage, and which is well adapted for the purposes described.

With the above and other objects in view, the invention consists of the improved luggage case frame construction, and its parts and combinations as set forth in the claims, and all equivalents thereof.

In the accompanying drawings in which the same reference characters indicate the same parts in all of the views:

Fig. 1 is a perspective view of a "soft-sided" hand luggage case in open condition, interior fittings and lining material being omitted and portions of the covering material of the case sections being broken away to show structural details of the improved frame construction;

Fig. 2 is an enlarged, fragmentary detail sectional view taken on line 2—2 of Fig. 1;

Fig. 3 is an enlarged fragmentary detail sectional view taken on line 3—3 of Fig. 1;

Fig. 4 is an enlarged fragmentary detail sectional view taken on line 4—4 of Fig. 1;

Fig. 5 is an enlarged fragmentary detail sectional view taken on line 5—5 of Fig. 1;

Fig. 6 is an enlarged fragmentary detail view of a case section rail construction at a corner, said view being indicated by the line 6—6 of Fig. 5;

Fig. 7 is an enlarged fragmentary detail sectional view taken on line 7—7 of Fig. 1;

Fig. 8 is an enlarged fragmentary detail sectional view of the meeting ends of a pair of rail members disconnected to show the tongue and groove connection of the same;

Fig. 9 is an enlarged fragmentary perspective view of an exterior corner portion of one section of the hand luggage case with the hinge strip broken away and in section;

Fig. 10 is a fragmentary detail sectional view taken on line 10—10 of Fig. 9; and

Fig. 11 is an inverted fragmentary plan view of a corner portion of a case section taken on line 11—11 of Fig. 1.

Referring now more particularly to the drawings, it will appear that the improved hand luggage case comprises a pair of complementary sections 12 and 13 whose open faces are adapted to be brought into meeting relationship when the case is closed. The luggage case is of the type having soft or non-rigid side walls. All outer

surface portions of the case section walls are covered by conventional flexible covering material, which on the better class of luggage is leather, but which may also be Fabrikoid, composition, plastic, canvas or the like. To accomplish the "soft-sided" feature of the walls, it will be observed from the drawings that the taut, tenacious flexible covering material 14 is not reinforced on the side wall portions of the case sections, but in practice the inner surfaces of the same are merely covered with conventional lining material (not shown). To give form to each case section a light weight interconnected and reinforced skeleton frame, generally of rectangular formation, is required, and the frames of the case sections are of the essence of the present invention. Those walls of the case sections which form the bottoms when the case is in its closed carrying position, are reinforced, as are the end walls and top walls, the latter carrying necessary handles 15 and latch hardware 16. The meeting edge portions of said reinforced bottom walls of the complementary sections 12 and 13 are hingedly connected together by hinge strips 29.

The construction of one of the complementary sections of the hand luggage case will now be described in detail. This is the case section 12 which is the deeper of the two sections, and it will be observed that it is of U-formation in longitudinal and transverse section and includes the soft or flexible side wall previously mentioned and the reinforced top and bottom, and end walls (referring to the position of the case in its closed, transportable condition).

The outline of the case section is defined by a rectangular frame formed of connected together wooden rails including outer and inner longitudinal rails 17 and end transverse rails 18. The meeting ends of the frame rails 17 and 18 are secured together by tongue and groove joints 19 and 20, as best shown in Fig. 8. The securement at the joints may be facilitated by the use of glue or other adhesive. With particular reference to the forward longitudinal rail 17, attention is directed to the construction shown in Fig. 3, wherein it will be observed that the underside of said rail is provided with a longitudinal slot 21 in which is secured the inner edge of a flat wooden or veneer frame strip 22, but the latter terminates short of the ends of the rail 17 as will be noted from Figs. 1 and 11 and for a purpose hereinafter to be dealt with. Nailed or otherwise secured to the outer face of the forward rail 17, as well as the end transverse rails 18, is a U-shaped valance strip or collar 23, preferably formed of fiber and said valance strip or collar projects beyond the outer surface of the rail frame to receive the rail frame of the section 13 of the luggage case when the case is in closed condition.

The end rails 18 are similarly formed with longitudinal grooves 24 (see Fig. 2) which receive the inner margins of end wall reinforcements 25 formed of fiber or the like. It will be observed from Figs. 1, 2, 3 and 4 that each end wall reinforcement 25 is not only co-extensive with its rail 18, but it is formed with integral angularly inturned end extremities 25' which interiorly overlap the front and rear strips 22 and 26 respectively and are fastened thereto by rivets 27 or other suitable securing means. The outer face of the rear longitudinal rail 17 is rabbeted to receive the inner edge of the rear strip 26, the latter being nailed or otherwise secured thereto and the joint forms a flush construction, as will appear from Fig. 4. The rear longitudinal strip 26 terminates short of the ends of the rear rail 17

in the same manner as was mentioned in connection with front strip 22. The rear or inner corners of the frame for the case section 12 are reinforced by curved metal plates 28 applied in the manner shown in Fig. 6. Said members 28 serve to reinforce the rail joints at the corners as well as engaging the adjacent portions of the strips 23 and 26.

One continuous sheet of covering material 14 is applied to the described frame of the case section 12 to cover the broad side wall thereof and to also cover the top and bottom walls. As will be noted from Fig. 1, the side wall of said case section is formed only of said covering material (with lining being applied thereto in actual practice) and the covering material is stretched and secured very tautly with the frame causing the same to bow outwardly slightly which effect, and a rounding adjacent the edges of the top and bottom portions is facilitated by bevelled edges 22' and 26' on the frame strips 22 and 26, respectively, as is shown in Figs. 3 and 4. As will be observed from Fig. 10, the covering material 14 may actually comprise several plies of secured together material. Relative to the top wall of the frame, the multi-ply covering material starts at and abuts against the shoulder formed by the valance strip 23 and it is stitched to the wooden frame element 22, as indicated by the line of stitching and designated 39 in Fig. 1. Relative to the bottom wall of the case section the covering material 14 is stitched to the wooden frame element 26 along the line 31 (see Figs. 9 and 10) and a suitable reduced thickness of the covering material is continued to provide the hinge strip 29, previously referred to. Adjacent the end walls of the case section the covering material is folded inwardly and forms the external edge bead 18', best shown in Figs. 1, 9 and 10.

The rectangular frame formed by the connected rails 17 and 18, as well as the valance or collar 23, is covered by a thin layer of covering material applied as is best shown in Figs. 1, 9 and 10 with edge portions thereof being secured inwardly of other applied layers of covering material.

The end walls of the frame have separate sheets of covering material applied thereto in the manner best shown in Fig. 10. Marginal portions thereof are folded in upon portions of the side covering. This bunching or extra thickness of material is accommodated by recesses formed at the ends of the top and bottom walls, which recesses result from the end faces of the top and bottom panels, the adjacent unlapped outer surfaces of the angular end wall extensions 25', and the adjacent overhanging rail portions 17 and 18, as will appear from Fig. 11.

Opposite end portions of the bottom wall of the case section under consideration have secured thereto by means of rivets which pass through and secure all thicknesses of material, metallic cleats 32. Also, the inner or lower corner portions of said case section are reinforced and braced by metallic corner plates 33 applied as best shown in Figs. 1, 9 and 10. Said metallic members 33 are secured by rivets to the valance strip 23 and the cover thereabout, and are also secured by pins to the rail 17.

The construction of the other of the complementary sections of the hand luggage case will now be described in detail, although in some respects, the frame of the case section 13 is built up in a manner very similar to that of the case section 12. The case section 13, it will be ob-

served, is also of U-formation in longitudinal and transverse section, and its side wall is soft or flexible, while the end walls and the top and bottom wall (referring to the position of the case in its closed transportable condition) are reinforced.

The outline of the case section 13 is defined by a rectangular frame formed of connected together wooden rails including outer and inner longitudinal rails 34 and end transverse rails 35. The meeting ends of the frame rails 34 and 35 are secured together by glued tongue and groove joints, as described in connection with the case section 12 and as is shown in Fig. 8. The top or outer wall of the case section 13 is reinforced by a relatively wide wooden or veneer frame panel 36 having its inner edge rabbeted into the outer face of the rail 34 to provide a flush joint. The outer longitudinal edge of the panel 36 is bevelled as at 36', to facilitate the application of the covering material 14. The panel 36 terminates short of each end of the rail 34. The reinforcement of the lower or inner wall of the case section 13 is identical to that just described in connection with the upper or outer wall.

The end walls of the case section 13 are reinforced by fiber strips 37 which are reduced in width intermediate their ends to lighten the construction and to give more flexibility to the applied covering material. As was the construction in connection with the end walls of the case section 12, the fiber reinforcements 37 have in-turned end flanges 37' which interiorly lap the end portions of the wooden panels 36 and are secured thereto, but being thinner than the wooden panels, form inwardly offset shoulders for the smooth application of the covering material to the ends and corners, as was described in connection with the case section 12. The corners are reinforced by curved metal brackets 28. Sheets of covering material are applied to the frame of the case section 13 in the same manner as described in connection with the case section 12.

Each section of the hand luggage case includes an open rectangular frame formed of wood and fiber elements which are thin and light and of a nature and form so as to preclude bulkiness in the finished piece of hand luggage. The longitudinal frame elements are securely attached at their ends to the transverse frame elements with the corner joints being reinforced and including overlapping extents. The various side and end panels are securely mounted in the rails so that each case section is extremely strong and rigid and will not be subject to distortion in

use, but maintains a desirable degree of flexibility and permits the application of flexible sheet covering material in a manner to preserve the "soft-sided" appearance and character of the hand luggage.

From the foregoing description, it will be seen that the improved frame construction for "soft-sided" luggage is simple, durable and light and is well adapted for the purposes described.

What is claimed as the invention is:

In a box-type hand luggage case, an open-faced section of U-form in section having rigid top, bottom and end walls including reinforcing panels therein and a flexible side wall having its edge portions secured to and covering the top and bottom walls, the top and bottom walls including rails into which marginal portions of the panels are rabbeted, said panels being of less length than the rails to provide overhanging rail portions, the end walls including rails formed with grooves into which marginal portions of the end wall panels are secured, the end wall panels having angular end extensions interiorly lapping, and secured to, end portions of the top and bottom wall panels, there being recesses at each end of said top and bottom walls, said recesses being formed by end faces of said top and bottom wall panels, by the adjacent unlapped outer surfaces of said angular end wall extensions, and by the adjacent overhanging rail portions, a sheet of flexible covering material applied to the outer face of each end wall panel, edge portions of the latter sheets being folded under and secured in superimposed relation to edge portions of the flexible wall and such superimposed edge portions being flushly accommodated within said recesses of the top and bottom walls.

GEORGE G. BARTON.
